CONTROL UNIT FOR MOTOR BOATS

John D. Smith, Selkirk, N. Y., assignor to Anti-Corrosive Metal Products Co. Inc., Schodack, N. Y., a corporation of New York

Application May 31, 1956, Serial No. 41,715

Term of patent 14 years

(Cl. D71—1)

Figure 1 is a perspective view of a control unit for motor boats, embodying my new design;

Figure 2 is a side elevational view of the control unit; and

Figure 3 is a top plan view of the control unit.

I claim:

The ornamental design for a control unit for motor boats, substantially as shown.
